[57] **CLAIM**

The ornamental design for a dental floss vial dispenser, as shown and described.

DESCRIPTION

FIG. 1 is a perspective view of a cap portion of the dental floss vial dispenser of the present invention;

FIG. 2 is a perspective view of the cap portion of FIG. 1 in an open configuration;

FIG. 3 is a top plan view of the cap portion of FIG. 2;

FIG. 4 is a bottom plan view of the cap portion of FIG. 2;

FIG. 5 is a right elevational view of the cap portion of FIG. 2;

FIG. 6 is a left elevational view of the cap portion of FIG. 2;

FIG. 7 is a rear elevational view of the cap portion of FIG. 2;

FIG. 8 is a front elevational view of the cap portion of FIG. 2;

FIG. 9 is a perspective view of the dental floss vial dispenser of the present invention; and,

FIG. 10 is a perspective view of the dental floss vial dispenser of FIG. 9, in an open configuration.
